DESIGN.

H. COHN.

THREE-WAY PLATE FOR LIGHTING FIXTURES.

APPLICATION FILED JAN. 13, 1921.

58,888.

Patented Sept. 6, 1921.

Inventor
Harry Cohn
By his Attorney *J. H. Parker*

UNITED STATES PATENT OFFICE.

HARRY COHN, OF BROOKLYN, NEW YORK, ASSIGNOR TO HYGRADE LIGHTING FIXTURE CORPORATION, OF BROOKLYN, NEW YORK, A CORPORATION OF NEW YORK.

DESIGN FOR A THREE-WAY PLATE FOR LIGHTING-FIXTURES.

58,888.

Specification for Design.

Patented Sept. 6, 1921.

Application filed January 13, 1921. Serial No. 437,092. Term of patent 7 years.

To all whom it may concern:

Be it known that I, HARRY COHN, a citizen of the United States, residing in Brooklyn, in the county of Kings and State of New York, have invented a new, original, and ornamental Design for a Three-Way Plate for Lighting-Fixtures, of which the following is a specification, reference being had to

the accompanying drawing, forming part thereof.

The figure is a plan view of a three-way plate for lighting fixtures.

I claim:

The ornamental design for a three-way plate for lighting fixtures, as shown.

HARRY COHN.
